ADJUSTABLE GOLF CLUB HEAD

Patrick H. Callaghan, Sr., Rochester, N. Y.; Leila Callaghan, administratrix of the estate of Patrick H. Callaghan, Sr., deceased

Application April 15, 1950, Serial No. 156,072

4 Claims. (Cl. 273—79)

1

This invention relates to golf clubs, and more particularly to a golf club having a head, the striking angle of which is adjustable from the grip end of the handle.

Golf clubs are generally provided in sets, the metal blades of individual clubs varying in angle, so that by selection of one or another club of the set, varying driving effects upon the ball may be had.

The object of this invention is to provide a single club having a blade adjustable with reference to the axis of the handle, so that the blade can be set at any angle within the range of angles generally supplied by a set of clubs, thus rendering it unnecessary to employ a set of clubs, each having a blade permanently set at a different angle from the others.

Another object of the invention is to provide the hollow handle of the club with a stem axially movable therewithin by a manual adjustment at the grip end of the handle and adapted to be held at any set position.

Another object of the invention is to provide in the head end of the handle a boss and socket in which the lower end of the stem moves axially and actuates an arbor mounted to rotate horizontally, which arbor is rigidly affixed to the blade of the club to turn therewith.

Another object of the invention is to provide a gearing between the head end of the stem and the arbor affixed to the blade, to rotate and hold the blade in any angular position to which it may be set by axial movement of the stem.

A further object of the invention is to provide a rugged construction providing for the aforesaid adjustment, capable of withstanding the stresses incident to golf clubs.

These and other objects of the invention will be illustrated in the drawings, described in the specification and pointed out in the claims at the end thereof.

In the drawings:

Fig. 1 is an elevation of the golf club and the blade viewed from the front, the grip end or top part of the handle being shown in section and the shaft part of the handle being broken away.

Fig. 2 is an elevation of the head or lower end of the handle and the stem and blade, the parts being viewed from the back.

Fig. 3 is an enlarged sectional view of the lower part of Fig. 1, the lower end of the handle and the boss and the blade being shown in section, showing the gearing by which the angular position of the blade is adjusted by the axial or end-

2

wise movement of the stem. The section is taken on the line 3x, 3x of Fig. 8.

Fig. 4 is an enlarged vertical section through the gearing and parts associated therewith, the section being taken on the line 4x, 4x of Fig. 3.

Fig. 5 is an enlarged cross section on the line 5x, 5x of Fig. 1 showing part of the mechanism for adjusting the stem endwise in the handle.

Fig. 6 is a section on the line 6x, 6x of Fig. 5, showing the cap and stem, the split sleeve and the grip end of the handle, the washer interposed between the end of the handle and the cap and the padding surrounding the handle and forming the grip.

Fig. 7 is an enlarged side elevation of the sleeve shown in section near the top of Fig. 1 which sleeve is contained inside of the grip end of the handle and surrounds the stem.

Fig. 8 is an end elevation of the blade and the lower part of the handle and stem as viewed from the left at the bottom of Fig. 1.

In the drawings, like reference numerals indicate like parts.

In the drawings, reference numeral 1 indicates the tubular shaft portion of the handle of a golf club and 2 indicates a stem that is made up of two parts, which stem is enclosed in the handle and moves endwise therein and is held against rotation therein as will presently be explained.

Enclosed in the grip end of the tubular handle is a split sleeve 3 shown in Figs. 1 and 7, which sleeve is held against rotation in the handle 1 by two pins 4 and 5 which pins are inserted in the tubular handle and engage in holes in the sleeve 3. These pins do not go through the stem 2.

At the upper end, the stem 2 is provided with a male thread. On the upper end of the stem 2 is placed a cap 6, which is threaded with a female thread that engages with the male thread on the upper end of the stem. This cap turns for the purpose of moving the stem endwise in a manner that will presently be described.

The split sleeve 3 has a mutilated flange at the top thereof. The sleeve is split so that the upper ends of it can be sprung together. The flange at the top is mutilated or cut away to form the small flanges 7 and 8 as shown in Figs. 1, 5, 6 and 7. The cap is formed with an annular groove 9 with which the small flanges 7 and 8 can engage when the upper end of the split sleeve is released and the ends are allowed to spring apart, it being understood that the upper ends of the split sleeve are pressed together so that the mutilated flanges can pass through the narrow

opening below the annular groove 9 until they are in line with the groove itself and are then allowed to spring apart. This permits the cap to rotate freely on the flanges.

When the stem 2 is inserted in the split sleeve 3 the mutilated flanges 7 and 8 are held in spread relation and securely held in the annular groove 9 of the cap 6. On the lower end of the stem 2 is the enlarged cylindrical stem end member 14. The end member 14 is provided with a socket into which the lower end of the stem 2 fits and the two parts are pinned by the pin 14a.

The split sleeve and the cap are first assembled in this manner and the upper end of the stem 2 is inserted into the opening of the bottom of the split sleeve 3, and makes threaded engagement with the cap 6. The stem and its assembly are held against rotation in a manner that will presently be described and the stem and the assembly are moved endwise by turning the cap 6.

On the lower end of the shaft portion of the handle 1 of the golf club is provided a casting 18, which has a bore therein aligned with the handle axis to receive the enlarged cylindrical end member 14 of the stem 2. The casting also has a horizontal bore therein to receive the arbor 19. The upper end of this casting is recessed to form a shoulder 20 on which the lower end of the handle shaft portion 1 rests. The parts are held together by a tight drive fit. They can be pinned together if needed. The casting comprises intersecting integral sleeves whose bore axes are askew to one another.

On the enlarged end member 14 is formed the teeth 15 of the rack 17. The enlarged end member is cylindrical and the crest of the teeth formed therein are therefore rounded. The arbor 19 is formed with gear teeth milled into it which when the arbor is inserted into place engage with the teeth of the rack as is shown in Figs. 3 and 4. The right hand end of the arbor is formed with a head 21. This arbor is inserted in the horizontal bore so that the rack and the gear teeth mesh with each other. On the left hand end of the arbor is placed the blade 22, which blade has a boss 24 on the back of it, which is recessed with a hole to receive the left hand end of the arbor 19, it being understood that the arbor and the blade are pinned together as indicated by the pin 23. The back of the blade is also reinforced by the ribs 25, 25.

The stem with the assembly at the upper end thereof, as above described, with the enlarged end member 14 at the lower end is inserted in the grip end of the handle with a washer 11 interposed between the lower end of the cap 6 and the top of the handle shaft portion 1, it being understood that the arbor 19 is first inserted in the horizontal hole in the casting 18. This brings the rack and gear shown in Figs. 3 and 4 in engagement with each other.

The teeth on the rack mesh with the teeth on the arbor and keep the stem 2 from rotating and limit it to an up and down movement.

The blade 22 is then placed on the arbor and is fastened to it by the pin 23.

Before the blade is placed on the arbor, the stem 2 and the rack 17 should be brought to the lower end of its movement against the set screw 26, which set screw is shown at the bottom of Fig. 4. This is done by turning the cap 6. In this position the flat side 22a of the blade 22 is set at its maximum angle to the handle which is preferably about (15 degrees) 15° below the horizontal which horizontal is determined by a line

perpendicular to the handle. This position is indicated by the dotted line shown in Fig. 8. The blade is then placed on the arbor at this angle and is pinned to the arbor. Thereafter the cap 5 is turned in the reverse direction to draw the stem 2 up until the flat side of the blade 22 stands parallel to the handle. The further upward movement of the stem is then limited by inserting a set screw 27 in the cap 6. In this way the endwise movement of the stem is limited by the set screw 27 at the top and the set screw 26 at the bottom. By the rotation of the cap 6 the blade can be turned through an angle of about (75 degrees) 75° and left at any angle in between these limits and is held securely in such position.

In this way, the endwise movement of the stem is limited to about $\frac{1}{16}$ or $\frac{3}{8}$ of an inch.

By this adjustment of the blade, one club can be made to serve the same purpose as a number 20 of clubs.

The upper end of the tubular handle shaft portion 1 is surrounded by a sleeve or a wrapping 30 for the purpose of forming a grip.

I claim:

1. A golf club comprising the combination of a tubular handle, a stem extending lengthwise therethrough, a split sleeve for said stem fixedly positioned in the upper end of said handle, said split sleeve having parallel arms outwardly flanged at their ends and held in spaced relation by said stem, a handle cap screw threaded on the end of said stem and having an internal annular thrust groove for receiving the flanged ends of said sleeve when held in spaced relation by said stem, said handle having at its lower end an integral member having a guideway bore for the lower end of said stem, and a transverse bore intersecting in offset relation with said guideway bore, a head member having a shank journaled in said transverse bore, said shank and stem having meshing gear and rack teeth, respectively, whereby said head member may be angularly set by lengthwise movement of said stem imposed by rotation of said handle cap, said integral member being effective to rigidly hold the teeth of said rack and gear in correct meshing relation, and form a housing for said stem and shank.

2. A golf club comprising a tubular handle, a stem extending lengthwise through said handle, manual means for moving said stem with respect to said tubular handle from one set position to another set position, and means for preventing lengthwise movement of said stem in the handle

55 when in a set position, said tubular handle terminating at its lower end in a sleeve having a guideway bore for constrained sliding movement of said stem therein, a transverse sleeve having a bore in the lower end of said handle, intersecting said guideway bore and offset therefrom, said transverse sleeve being integral with said first-named sleeve, a head member having a shank journaled in said offset bore, said shank and stem having meshing gear and stem teeth, respectively,

60 the integral sleeve at the lower end of said handle forming a rigid housing for said stem and shank, and maintaining the gear and stem teeth in positive engaging relationship.

3. A golf club comprising the combination of an elongated handle having a grip at one end, a stem therein, means for positively and gradually moving the stem lengthwise in the handle in either direction, said means including thrust means coacting between said moving means and said handle to prevent lengthwise movement of

said moving means, a rack on the lower end of the stem having teeth thereon, an arbor mounted to rotate in the lower end of the handle and extending transversely therefrom, a blade mounted on said arbor and turning therewith, teeth formed in said arbor engaging the teeth of said rack and turned thereby on the lengthwise movement of the stem, the teeth on the arbor engaging with the teeth on the rack and being adapted to hold the stem against turning, the lower end of said handle being integral and having askew intersecting bores providing guideways for said rack and arbor, respectively.

4. A golf club comprising the combination of an elongated hollow handle having a hollow shaft portion and a casting on the bottom end thereof, said casting having a cylindrical opening therein axially aligned with the hollow shaft portion, one end of which opening is enlarged in diameter to form a shoulder and receive the lower end of the shaft portion, and on which shoulder the end of the shaft portion rests, said casting being held against rotation in the shaft portion, a stem extending through the handle and having an enlarged cylindrical end on the lower end thereof, slideable axially in the opening of said casting, teeth on the enlarged cylin-

drical end forming a rack thereon, a boss extending laterally on said casting having a cylindrical opening therein intersecting but offset from said first-named opening, an arbor mounted to turn in said boss and casting, teeth formed on said arbor in engagement with the teeth on the rack at the intersection of said openings, and a blade fastened on the end of said arbor, said casting forming an integral housing including a snug guideway for said toothed stem, and a journal for said arbor and arbor teeth, whereby to hold said toothed stem and arbor teeth rigidly in proper meshing relation.
